UNITED STATES PATENT OFFICE.

THOMAS J. FOSTER, OF RIDGEWOOD, NEW JERSEY.

FLOOR CONSTRUCTION.

Application filed February 9, 1926. Serial No. 86,992.

This invention relates to certain improvements in floor constructions and has been designed particularly for constructing floors of comparatively small areas, such as houses, 5 apartment houses, and the like.

As now largely constructed, side or end girders are used of the I-beam type, that is, girders having upper and lower flanges. These girders act as supports for lighter 10 beams or girders which are positioned between them to form the floor, these lighter beams also acting as supports for a ceiling beneath them. These floor beams are of metal and are secured to the girders by riveting. This takes time and adds considerably 15 to the cost of construction.

The main object of the present invention is to produce a floor structure in which the cross beams or floor beams are secured to 20 the side or end girders by means which are independent of either, so that the floor beams can be supported from the girders without any rivets and can thus be put in place quickly and inexpensively.

25 A further object of the invention is to provide an improved securing device by which the floor beams can be supported from the side or end girders.

With these and other objects not specifically referred to in view, the invention 30 consists in certain novel parts, arrangements and combinations which will be described in connection with the accompanying drawings and the novel features pointed out in the 35 claims hereunto annexed.

In these drawings—

Figure 1 is a side view of the improved floor arrangement;

40 Figure 2 is a plan view showing the invention as employed in a floor construction which is, say a room wide, as, for instance, an ordinary house, the girders being shown in section in Fig. 1;

45 Figure 3 is a view of the left hand side of Fig. 1, on an enlarged scale, showing one form of the improved supporting beam section;

50 Figure 4 is a plan view of the same looking in the direction of arrow 4 of Fig. 3;

Figure 5 is a sectional detail view looking in the direction of arrow 5 of Fig. 3;

55 Figure 6 is a detail sectional view of the beam section shown in the preceding figures;

Figure 7 is a detail sectional view of a modified form of beam section which may be

employed where floor beams are to be supported from opposite sides of a main girder, as in a two or more room wide structure;

Figure 8 is a detail sectional view looking in the direction of arrow 8 of Fig. 7;

Figure 9 is a detail sectional view similar to Fig. 8 showing a modified form of beam section which may be employed;

Figure 10 is a plan view of the beam section shown in Fig. 11;

Figure 11 is a perspective view of the modified form of beam section shown in Fig. 9, and

Figure 12 is a detail sectional view of a beam section which may be employed where it is desired to support the floor beams below the main beams.

Referring now to these drawings and first to Fig. 1, the main side or end beams or girders are indicated by the numerals 1, 2. These are of I-construction, having top flanges 3 and bottom flanges 4, and these beams are supported from any suitable support or standard, not illustrated. These 75 main girders support the floor beams, marked 5, which extend between the main beams, three such beams being shown in Fig. 2.

In the construction shown in these figures it may be assumed that a one room wide 80 floor is being constructed. In accordance with the invention, means are provided whereby the floor beams may be supported from the main side beams or girders without riveting, the securing means being independent 85 of the girders and the floor means. While these beams may vary to a considerable extent in character, in the particular construction shown, short beam sections are provided which lock around under a flange 90 of the main beams and support the floor beams, the floor beams simply resting on these sections, these sections being in effect short cantilever beams which take the load 95 thrust of the floor beams. It will be understood, of course, that the beam sections have sufficient strength to support the weight of 100 the floor beams and the expected load which the floor beams are to carry.

These beam sections may vary widely in 105 form and construction. In the particular construction illustrated, however, and referring first to Figs. 1 to 6, there is provided a beam section having sides 6, 7 and a base 8. The floor beams are provided with 110 an upper flange 9 and preferably a lower flange 10, from which a ceiling structure may

be supported. The sides 6, 7 of the section lie beneath the edges of the flange 9 of the floor beams, the floor beams resting on these flanges. The beam section may be secured to the main girder in various ways. As shown, the beam section is formed by bending over the base at the front to form a locking tongue 11, which is turned around and under one side, as 12, of the top flange of the main girder. Means are provided for preventing sidewise displacement of the section, which may be in the form of a narrow tongue 13 which is bent around under the opposite edge 14 of the main side beam.

It will be observed that the web of the floor beam is positioned in the slot 13 formed by cutting out the tongue 13. This prevents any lateral movement of the beam and as the beam is supported on each edge of the beam section any tipping or rocking of the beam is effectually prevented.

With this construction it will be seen that the floor beams may very readily and quickly be positioned without requiring any riveting or any other securing devices, and by simply placing them in position on the sections, the sections having been secured to the girders. It will be understood, of course, that a section will be provided for each end of a floor beam, as shown in Fig. 1.

Where a floor is to be assembled in which the floor beams are located on each side of the main girder, a section such as shown in Fig. 7 may be employed. In this section locking tongues 15, 16 are cut out from the base at opposite ends of the section, and these are bent around the edges 12 and 14 of the flange 3 of the main girder. The section is dimensioned so as to extend beyond the girder at each side and thus can support the adjacent ends of two floor beams.

If desired, the sides 6, 7 of the section may be turned in, as indicated at 17 in Fig. 11, to form ledges on which the flange 9 may rest. A slot, as 18, may be left through which the web 20 of the floor beam may pass.

With the construction so far described, it will be seen that the floor beams are supported somewhat above the main girders.

Under some circumstances, it may be desirable that they be supported below, and in Fig. 12 a section for effecting this is provided in which the section is formed with a downwardly extending extension 21 on which the floor beams rest, the side play of the section being prevented by forming the downwardly extending part with an acute angle, as indicated at 22, this forming a stop and preventing displacement of the hanger.

While the invention has been shown and described in what is believed to be its best forms, it will be understood that certain changes and variations may be made in the specific construction of the hanger without departing from the invention as defined in the appended claims.

What I claim is:

1. In a floor construction, the combination of side or end I-girders, a beam section having a part engaging the top surface of the girder and a part extending laterally from the girder and forming a flanged beam seat clear of the web of the girder, and an I-floor beam supported by its upper flanges on the flanges of the beam section, said beam section being held in place by bending a part thereof under the top flange of the girder.

2. In a floor construction, the combination of side or end I-girders, a beam section having a part engaging the top flange of the girder and portions extending laterally on each side of the girder and clear of the girder web, and I-floor beams supported by their top flanges on the flanges of the beam section, said beam section being held in position by bending parts thereof under the top flanges of the girder.

3. A beam section for supporting I-floor beams having a part arranged to lockingly engage the top surface of the girder and laterally extending flanged portions on each side thereof on which floor beams may be supported, and locking tongues for locking the beam section to the top flange of the girder.

In testimony whereof, I have hereunto set my hand.

THOMAS J. FOSTER.
